CLAIM

The ornamental design for a chlorine dispenser for swimming pools, as shown and described.

DESCRIPTION

FIG. 1 is a top, front perspective view of a chlorine dispenser for swimming pools showing my new design;

FIG. 2 is a top plan view thereof;

FIG. 3 is a bottom plan view thereof;

FIG. 4 is a rear elevational view thereof; and

FIG. 5 is a right elevational view thereof, the left side being, identical.

The indentations on the side of the dispenser as shown in FIG. 1 are conical.
